US0D1104253S

(12) **United States Design Patent** (10) Patent No.: **US D1,104,253 S**
(45) Date of Patent: ** Dec. 2, 2025

(54) **CATHETER HOUSING**

(71) Applicant: **TIK d.o.o.**, Kobarid (SI)

(72) Inventor: **Martin Zupancic**, Ljubljana (SI)

(73) Assignee: **TIK d.o.o.**, Kobarid (SI)

(**) Term: **15 Years**

(21) Appl. No.: **35/522,059**

(22) Filed: **Jul. 25, 2024**

(80) **Hague Agreement Data**

Int. Filing Date: **Jul. 25, 2024**

Int. Reg. No.: **DM/239189**

Int. Reg. Date: **Jul. 25, 2024**

Int. Reg. Pub. Date: **Aug. 23, 2024**

(30) **Foreign Application Priority Data**

Feb. 19, 2024 (WO) DM/235578

(51) **LOC (15) Cl.** **24-02**

(52) **U.S. Cl.**

USPC **D24/112**
